UNITED STATES PATENT OFFICE

153,959

DESIGN FOR A DOLLY

Frank T. Loser, Oak Park, Ill.

Application May 13, 1946, Serial No. 129,659

Term of patent 14 years

(Cl. D54—13)

To all whom it may concern:

Be it known that I, Frank T. Loser, a citizen of the United States, residing at Oak Park, in the county of Cook and State of Illinois, have invented a new, original, and ornamental Design for a Dolly, of which the following is a specification, reference being had to the accompanying drawing, forming part thereof.

Figure 1 is a top view of a dolly showing my new design.

Figure 2 is a side view thereof.

Figure 3 is an end view thereof.

Figure 4 is a view of the opposite end of the device as shown in Figure 3.

I claim:

The ornamental design for a dolly, as shown.
FRANK T. LOSER.
